UNITED STATES PATENT OFFICE.

HARRY W. FRENCH, OF SYRACUSE, NEW YORK.

WARM-AIR FURNACE.

Application filed October 4, 1927. Serial No. 223,910.

This invention relates to a warm air furnace but more particularly to the means for pre-heating the cold air upon its entrance into the warm air chamber of the heater 5 preparatory to distribution to the rooms to be heated.

I am aware that various devices have heretofore been proposed for heating the air in transit from an external source of supply to 10 the lower end of the warm air casing by causing the cold air to flow from the top downwardly around the exterior of the warm air casing but in most of the constructions with which I am familiar the cold air jacket 15 rounding the warm air casing is cylindrical from top to bottom and require the use of a supporting base of corresponding large diameter and, therefore, of special construction different from that ordinarily used in furnaces which not only requires a larger floor 20 space for the furnace, but also prevents the use of the jacket with standard makes of furnaces without making a special supporting base for the jacket.

25 The main object, therefore, of my present invention is to provide a cold air jacket which may be mounted upon standard forms and sizes of furnaces without increasing the floor area of the base and also to enable the cold 30 air inlet pipes and warm air outlet pipes to be more conveniently arranged around the top of the furnace with the cold inlet pipe or pipes overhead and wholly above the plane of the firepot.

35 Another object is to permit the use of a water pan on the base around the ash box and within the smaller end of the tapered bottom of the cold air jacket near the junction of the bottom of the cold air chamber with the 40 bottom of the warm air chamber so as to carry the moist vapor from the pan upwardly into the warm air chamber by the natural circulation of the cold and warm air currents.

45 Other objects and uses relating to specific parts of the furnace will be brought out in the following description.

In the drawings:—

50 Figure 1 is a perspective view of a warm air furnace equipped with my improved cold air jacket and other features of my invention.

55 Figure 2 is a horizontal sectional view taken in the plane of line 2—2, Figure 3.

Figure 3 is a vertical sectional view of the 60 same furnace taken in the plane of line 3—3, Figure 1.

65 Figure 4 is a detail sectional view, partly

broken away, taken in the plane of line 4—4, Figure 3.

The standard constructions of furnaces are usually equipped with a substantially circular base ring or frame —1— carrying a suitable ash box —2— which, in turn, supports a fire pot —3—.

These standard furnaces are also equipped with some form of head radiator as —4— 65 which, in this instance, is mounted upon the upper end of the fire box —3— and is provided with a central opening —5— closed at the top but open at the bottom for receiving the products of combustion from the interior 70 of the fire pot —3—.

The opening —5— is provided in its front side with a passage —6— connecting it with an annular chamber —7— which is formed in the radiator around the opening —5— and is provided in its rear side with an outlet —8— communicating with the smoke flue as —9—, the latter being adapted to be connected to any available chimney or other outlet to the atmosphere in any well-known manner 80 not necessary to herein illustrate or describe.

The front wall of the chamber —7— may be provided with a clean-out opening —10— normally closed by a door —11—. The fire pot —3— and radiator —4— are inclosed 85 within an upright cylindrical casing —12— mainly concentric therewith and in spaced relation thereto to form an intervening warm air chamber —13—, said casing being supported upon the fire box —3— by means of 90 brackets or braces —14— as shown more clearly in Figure 3.

The front side of the jacket —12— is provided with a cast metal front plate —12'— having suitable openings communicating 95 with the ash box —2— and fire pot —3— respectively but normally closed by openings —15— and —16—, the front plate —12'— being extended from the base ring —1— to the upper edge of the casing —12— and suitably secured thereto to form air and gas-tight joints therewith.

The casing —12— is open at the bottom to allow the cold air to pass therethrough upwardly and is also open at the top to allow the 105 warm air to pass out through suitable distributing pipes —17— adapted to be extended to the rooms to be heated.

The casing —12— is inclosed within an outer cold air shell or jacket —18— having 110 a downwardly tapered lower end —19— and an upwardly tapered upper end —20— while

the main body or intermediate portion thereof is cylindrical and extended circumferentially around the major portion of the casing —12— in spaced relation thereto to form an 5 intervening cold air chamber —21—.

The lower smaller end of the tapered portion —19— is made to conform to the diameter of the base ring —1— and is operatively mounted thereon to form an air and gas-tight 10 joint therewith while the upper end of said tapered portion —19— extends to about the level of the lower end of the casing —12— in spaced relation thereto to allow the cold air to pass from the chamber —21— downwardly 15 into the tapered portion —19— which serves as a convenient means for deflecting the downwardly flowing current of air inwardly for upward circulation through the open lower end of the casing —12— or between 20 said casing and the fire box —3— where the cold air is further heated for upward delivery through the distributing pipes —17—.

The upper end of the cylindrical portion of the casing —18— terminates at a level 25 some distance below the upper end of the casing —12— while the upper tapered portion —20— of the jacket —18— extends across the upper end of the casing —12— and is firmly secured thereto to form an air and gas-tight 30 joint therewith.

The tapered upper end —20— of the cold air jacket —18— forms the top walls of the warm air chamber —13— and cold air chamber —21— and serves not only to receive the 35 warm air distributing pipes —17—, but also to receive and support the adjacent ends of suitable cold air inlet pipes —22— which may be connected to any available source of cold or fresh air supply.

The smaller upper end of the tapered portion —20— of the cold air jacket —18— is provided with a depressed conical portion having its apex substantially co-axial with the axis of the casing —12— and extending 40 some distance into the upper end of said casing or in proximity to the upper surface of the radiator —7— to assist in deflecting the warm air from the upper portion of the casing laterally and upwardly through the distributing pipes —17—.

The front cast metal plate —12'— forms a continuation of the cylindrical casing —12— across the front of the furnace while the cold air jacket —18— terminates at opposite sides of the plate —12'— in planes substantially radial to the vertical axis of the furnace to form an intervening open space at the front for the swinging of the doors —11—, —16— and —15— and to facilitate 45 the insertion of fuel and removal of the ashes into and from the furnace.

The ends of the jacket —18— at the front are united to the adjacent portions of the casing —12— by end walls —24— extending 50 from top to bottom of the cylindrical portion

—18— and from top to bottom of the cast metal plate —12'— for confining the cold air within the chamber —21— in its transit downwardly through said chamber from the cold air inlets —22— to the underside of the 70 bottom of the casing —12—.

A water pan —25— is supported within the lower or smaller end of the tapered portion —19— of the jacket —18— directly upon the base —1— and around the ash box —2— so that its upper open side may be disposed in the path of travel of the cold air from the chamber —21— into the warm air chamber —13—. 75

Under these conditions the watery vapor will be carried by the current of air passing from the cold air chamber to the warm air chamber around the lower edge of the casing —12— to mingle the vapor with the warm air rising in the warm air chamber and thereby to cause the vapor to pass out through the distributing pipes —17— into the room to be heated. 80

Operation.

90

When the furnace is in operation for heating purposes the cold air entering the inlet pipes —22— in the upward tapered end of the jacket —18— passes downwardly from the chamber —21— around and into the lower end of the warm air chamber —13— where it is heated to the required temperature and delivered upwardly and outwardly through the distributing pipes —17— into the room or rooms to be heated and during this downward flow of the cold air through the chamber —21— said air is more or less pre-heated by radiation from the jacket —12— so that it enters the warm air chamber —13— in a more or less heated condition and is then further heated in the chamber —13— for delivery through the outlet pipes —17— as previously described. 100

As the pre-heated air from the lower end of the chamber —21— passes around the lower edge of and into the chamber —13— it carries with it the watery vapor which may be released from the pan —25— thereby supplying the necessary humidity to the warm air as it passes into the rooms to be heated. 110

What I claim is:—

The combination with a furnace having a base, an ash-box mounted on the base, a firepot mounted on the ash-box and a warm air casing mounted upon and surrounding the firepot in spaced relation thereto, and having its lower end open and terminating in a plane some distance above the base, of a cold air jacket comprising an upright portion surrounding the casing in spaced relation thereto beyond the marginal edge of the base and having its lower end terminating in substantially the same plane as the lower end of said casing and its upper end terminating some distance below the level of the upper end of 120

125

130

135

the casing, said jacket having a downwardly tapered bottom portion extending from the lower end of the upright portion to the marginal edge of the base, and an upwardly tapered top portion extending from the upper edge of the upright portion to the upper end of the casing and provided with a cold air inlet, and a top wall for the casing having

its outer marginal portion tapered upwardly and united to the tapered top portion of the jacket to form a continuation thereof and provided with warm air outlets.

In witness whereof I have hereunto set my hand, this 26th day of September, 1927.

HARRY W. FRENCH.
